UNITED STATES PATENT OFFICE.

SAMUEL JIMÉNEZ, OF SAN ANTONIO, TEXAS.

TIME-CONTROLLED SWITCH.

Application filed September 10, 1925. Serial No. 55,515.

This invention relates to new and useful improvements in electric switches, and particularly to that class of electric switches which are controlled by timepieces.

One object of the invention is to provide a device of this character wherein the switch is of simple construction, and wherein the duration of the electrical contact is regulatable.

Another object is to provide, in combination with the dial and mechanism of a clock, a dial driven by the minute hand arbor which carries spaced adjustable contacts for actuating a switch arm, whereby to close a circuit and maintain the circuit closed for the desired period of time.

Another object is to provide a device of this character wherein the current may be closed during any period of time of the day or night.

Other objects and advantages will be apparent from the following description when taken in connection with the accompanying drawings.

In the drawings:

Figure 1 is a front elevation of a clock in connection with which the switch is used, the wiring being shown in diagrammatic form, the clock being partly broken.

Figure 2 is a fragmentary front elevation, the smaller dial being partly broken away.

Figure 3 is a vertical section on the line 3—3 of Figure 2.

Figure 4 is a vertical section on the line 4—4 of Figure 2, showing the switch arm and the contacts carried by the smaller dial, and looking in the direction of the dial of the clock, the switch arm being engaged and partly elevated by one of the contacts.

Figure 5 is an enlarged vertical sectional view on the line 5—5 of Figure 2.

Figure 6 is a sectional detail view on the line 6—6 of Figure 2, showing the pivotal mounting of the arm 28.

Referring particularly to the accompanying drawings, 10 represents the dial of a clock, which dial is formed with a circular opening 11, in its upper portion. In rear of the dial is the usual clock train of gears 12, which include the minute hand arbor 13, said arbor being provided with the gear 14. The gear train is mounted in the frame 15, and extending between the front and rear plates of the frame, and secured therein, are the sleeves of insulation 16 and 17. Through

the sleeve 16 there is disposed an electric conducting wire 18, one end of which is connected with a terminal binding post 19, on the rear of the frame, and insulated from the casing by the insulated washer 20, while the other end is metallically secured to the clock frame. Rotatable in an insulated bushing in the front plate of the frame 15, is a shaft 21, which projects forwardly from said plate and carries on its forward end the smaller dial 22, said dial being rotatably disposed within the before-mentioned opening 11, of the dial 10, of the clock. A nut 23, on the forward end of the shaft 21 holds the dial 22 thereon, and causes the dial to turn therewith. The periphery of the dial 22 is toothed, as shown at 22', and meshes with an insulated gear 24 on a shaft 25, which carries a gear 26 meshing with the gear 14 of the minute hand arbor 13, whereby said dial is properly insulated from the remaining metal portions of the clock mechanism. Pivotally mounted adjacent one of the posts 27, on the clock frame 15, is a curved metal arm 28, the free end of which is formed with an elongated portion 29, to which more particular reference will be made later herein. The rear end of the shaft 21 is threaded and engaged in a nut 31, at the rear of the front plate of the frame 15. The forward end of the insulated sleeve 17 is threaded into the other end of the nut 31, and binds the adjacent end of the wire 30 against the end of the shaft 21, whereby to produce metallic contact therebetween. The wire 30 is disposed through the sleeve 17 and is connected with a binding terminal 32, on the rear of the clock. Current conducting wire 33 and 34 are connected respectively to the terminals 19 and 32, such wires being also connected with the socket of the lamp 35, and the screw plug 36, which latter is adapted to be screwed into the ordinary lamp socket. Loosely rotatable on the shaft 21 are the radial metal arms 37 and 38, the outer end of each of which is provided with a threaded opening for the reception of one of the threaded stems 39—40. These stems 39 and 40 are provided with the heads 41 and 42, respectively, the former being white and the latter black. These stems are disposed through the arcuate slot 43, formed in the smaller dial 22, adjacent the periphery thereof, and the heads 41 and 42 are disposed outwardly of the face of said dial for ma-

nipulation to loosen and tighten said heads whereby to permit rotation of the arms on the shaft 21 and adjustment of the stems longitudinally in the slot. The inner ends 8 of the stems 39 and 40 project into position for engagement with the elongated end of the switch arm 28, to lift said arm out of engagement with the insulated sleeve 44, which is carried by another post 45, of the 10 frame. The face of the dial 22 is divided diametrically into two portions, one of which is white, while the other is black, as clearly seen in Figure 1, the slot 43 being formed in the white portion, while a series 15 of internally threaded openings 46 are formed in the black portion, adjacent the periphery thereof. The stems are adapted to be engaged in these openings 46 and into the openings in the ends of the radial arms 20 37 and 38. The adjustments of the stems in the slot 43 are for the daylight hours, while the adjustments of the stems in the openings 46 are for the night hours. The dial 22 is driven by the minute hand arbor, and there- 25 by rotates synchronously therewith.

The screw plug 36 being properly screwed into an electric socket, and the current turned on, the heads 41 and 42 are loosened so that the operator may move the stems in 30 the slot 43 to the desired hour marked on the dial 22. If the lights of a store are to be turned on at 7 o'clock in the evening, the white head is moved until it is opposite the number 7 in the black portion of the dial, 35 after which the black head is moved until it is opposite the desired hour for the lights to be turned off, which may be 5 o'clock in the morning. As the clock train turns the hands about the main dial, and the hour of 40 7 o'clock is reached, the inner end of the stem 39 will engage with the elongated portion of the switch arm 28, elevating the same from the sleeve 44. Upon contact of the stem 39 with the arm 28, a circuit is completed through the frame of the clock, the wires 18 and 30, the dial 22, its shaft, the stem 39, and arm 28, whereupon the lamps will be lighted in the store. As the dial 22 continues to rotate the circuit will remain closed 45 and the arm 28 be finally released from the stem 39, to fall upon the stem 40, which has, by this time reached the proper position for this operation. The arm 28 is again lifted by the stem 40 and held in such position, to 50 retain the closed circuit, and the lamps in lighted condition, until said stem has passed from beneath the other end of the elongated portion of the arm, when said arm will fall onto the insulated sleeve 44, thus breaking 55 the circuit and extinguishing the lamps.

The elongated end of the switch arm is of

sufficient length to permit the stem 39 to remain in contact therewith for a period of four or more hours, and at the end of this period, when the arm is released from the stem 60 39, it falls onto the stem 40, so that the circuit is held closed for another period of hours, which will vary in accordance with the position of this stem with relation to the stem 39. 70

To normally urge the arm 28 downwardly against the insulation 44, a coil spring 47 is connected to the arm 28, at one end, and has its other end disposed through the insulated bushing 48, into metallic contact with the adjacent end of the wire 18, also secured in said bushing. By this metallic contact between the spring and the wire, current is transmitted to the switch arm 28. 75

Within the pivot opening of the arm 28 is 80 an insulated bushing 49 which is engaged on the stub shaft 27', a nut 50 being engaged on the rear end of the shaft, while a nut 51 is engaged on the forward end thereof, the former cooperating with a flange 52, on the 85 shaft to hold the shaft on the frame 15.

What is claimed is:

1. A time switch including a pivoted arm having an elongated terminal, a rotatable member, an insulated member normally engaged by said terminal, and a pair of spaced and adjustable contacts on the rotatable member one of which is arranged to engage the terminal and move the arm away from the insulated member to close a circuit for a 90 predetermined period of time, the other contact being arranged to engage the said terminal immediately upon release from the first contact to hold the arm away from the insulated member and to maintain the circuit closed for a second period of time and to finally release the arm for contact with the insulated member whereby to break the circuit. 100

2. The combination with a clock train and 105 the dial thereof having an opening adjacent its periphery, of a dial operated by the clock train and rotatable within the opening of the first dial, said second dial having a shaft, and openings adjacent its periphery, contact 110 pins adjustable in the openings of the second dial, an insulated stop member, and a pivoted switch arm having an elongated free end normally resting on said stop member and being arranged to be engaged and elevated successively by the contact pins whereby to close and maintain a circuit during a 115 period of time determined by the position of said contact pins.

In testimony whereof, I affix my signature.

SAMUEL JIMÉNEZ.
